UNITED STATES PATENT OFFICE.

RONDO J. BLACKBURN, OF BULLS GAP, TENNESSEE.

CAR-DOOR FASTENER.

1,164,456.

Specification of Letters Patent. Patented Dec. 14, 1915.

Application filed March 12, 1915. Serial No. 13,908.

To all whom it may concern:

Be it known that I, RONDO J. BLACKBURN, a citizen of the United States, residing at Bulls Gap, in the county of Hawkins and State of Tennessee, have invented certain new and useful Improvements in Car-Door Fasteners, of which the following is a specification.

While the invention is intended most especially to provide novel locking means for car doors, the same may be applied with equal advantage to sliding doors of any type.

The main reason for adapting the fastening means most especially to car doors is the feature whereby the door is moved laterally and drawn close against the side of the car, thereby preventing the formation of any crack or space which would admit of the waste of grain, plaster or other similar commodity stored in the car for transportation.

A further purpose of the invention is the provision of simple and effective fastening means which may be readily operated and which may be adjusted so as to prevent any part projecting so as to be in the way or liable to cause injury by striking an object.

With these and other objects in view, which will readily appear as the nature of the invention is better understood, the same consists in the improved construction and novel arrangement and combination of parts which will be hereinafter fully described and particularly claimed.

In the accompanying drawings has been illustrated a simple and preferred form of the invention, it being, however, understood that no limitation is necessarily made to the precise structural details therein exhibited, but that changes, alterations and modifications within the scope of the invention as claimed may be resorted to when desired.

Referring to the drawings, — Figure 1 is a view in elevation of part of a box car provided with a door embodying fastening means constructed in accordance with the invention; Fig. 2 is a horizontal section on the line 2—2 of Fig. 1; Fig. 3 is a vertical section on the line 3—3 of Fig. 1 showing the relation of the parts when the door is closed and fastened; Fig. 4 is a view similar to Fig. 3 showing the operating lever released; Fig. 5 is a view similar to Fig. 3 showing the fastener fully released; Fig. 6 is a detail view in perspective of the means for securing the operating lever in locked position; Fig. 7 is a detail view showing more clearly

the pivotal connection between the operating lever and shaft.

Corresponding and like parts are referred to in the following description and indicated in all the views of the drawings by the same reference characters.

The numeral 1 designates the side of a box car which is provided with an opening adapted to be closed by means of a sliding door 2 mounted to run upon an overhead track 3 and provided with hangers 4 to travel upon such track. The lower end of the door is retained in proper position by means of a guide 5 which is secured to the car below the door opening and engages the lower portion of the door so as to retain it in the proper position. A stop 6 is located at one side of the door opening to limit the closing of the door. A bracket stop 7 is disposed upon the side of the car some distance from the door opening to limit the movement of the door when slid into open position.

A shaft 8 is arranged upon the outer side of the door and extends lengthwise thereof and is provided at opposite ends with arms 9, which curve throughout their length and terminate in projections 10. The arms 9 are disposed at a right angle to the length of the shaft 8 and project through openings 11 formed in the door 2 near opposite vertical edge portions thereof. A recess 12 is in communication with the inner end of each opening 11 and is disposed above such opening formed in the inner or rear side of the door. The recesses 12 are of a length and depth to receive the projections 10 of the locking arms 9 when the latter are withdrawn to a position to release the door and admit of the same being slid either into open or closed position. A pin 13 intersects each of the openings 11 and sustains the wear incident to the movements of the locking arms as well as assisting materially in securing the door. Openings 14 are formed in the side of the car adjacent the door opening and are adapted to register with the openings 11 when the door is in closed position so as to receive the locking arms 9 when projected into locking engagement with the car.

A pin 15 intersects each of the openings 14 and engages the curved end of the locking arm 9 when projected through the opening 14. Strips 16 are attached to the inner wall of the side of the car and receive and house the inner ends of the locking arms 9 when the latter are projected into engagement.

with the car to secure the door. When the door is locked the outer ends of the locking arms 9 extend across the pins 15, as shown most clearly in Fig. 3, thereby drawing the door 2 close against the side of the car and preventing any possible outward movement of the door. It is also noted that the arms 9 extend across the openings 11 and 14 and thereby prevent sliding movement of the door into open position. The shaft 8 is mounted so as to receive a two-fold movement, the one being slideable vertically along the outer side of the door 2 and the other pivotal to admit of withdrawing and projecting the locking arms. These two movements are simultaneous and are essential to the proper operation of the locking arms.

Keepers 17 are located upon the outer side of the door near the vertical edges thereof and receive opposite end portions of the shaft 8. These keepers retain the shaft in proper position and direct it in its vertical sliding movements. An operating lever 18 is pivotally connected to the shaft 8 and is formed at its pivotal end with flange portions between which a lug 19 is received, a pivot 20 passing through registering openings in the overlapping parts and serving to pivotally connect the lever 18 to the lug. The operating lever 18 is formed near its free end with a slot through which passes a latch member 21 pivotally connected to a bracket 22 which is secured to the door 2 above the pivot fastening of the lever 18 with the shaft 8. The latch member 21 is substantially of L-shape and one member is adapted to extend along side an ear 23 projecting outwardly from the bracket 22, both parts being apertured to receive a seal 24 to secure the operating lever in locked position.

A sliding door provided with locking means embodying the invention is adapted to be drawn close against the part in which the door opening is formed and is at the same time adapted to be secured against being opened. When the door is closed the shaft 8 is moved upward and at the same time turned, thereby projecting the locking arms 9 through the openings 11 and 14 and engaging the pins 13 and 15, such operating lever being secured by the latch member hereinbefore stated. When the door is released the shaft 8 occupies a position at the lower ends of the keepers 17, as indicated most clearly in Fig. 5 and the operating lever 18 is turned so as to lie close against the shaft and side of the door so as not to be in the way.

Having thus described the invention, what is claimed as new is:

1. A fastener comprising a shaft mounted to receive both a pivotal and a lateral slid-

ing movement and provided with an off-standing locking arm which is projected or withdrawn by the combined pivotal and sliding movements of the shaft.

2. A fastener comprising a shaft mounted to receive a pivotal and lateral sliding movement and provided with a curved locking arm projecting therefrom substantially at a right angle, and a keeper for engaging the shaft and retaining it in proper position during its pivotal and lateral sliding movements.

3. In combination with a part having an opening and a sliding door for closing such opening, a shaft mounted upon the door and adapted to receive a combined pivotal and sliding movement, locking arms projecting from the extremities of the shaft and forming a part thereof and adapted to pass through the door and engage the part in which the door opening is formed, such locking arms being curved throughout their length and adapted to draw the door toward the part in which the door opening is formed.

4. A door fastener comprising a shaft mounted to receive a combined pivotal and lateral sliding movement and formed with off-standing locking arms which curve throughout their length and terminate with projections forming stops, said locking arms being disposed to operate through lateral openings formed in the part upon which the shaft is mounted and such lateral openings having recesses in communication therewith to receive the projections of the locking arms.

5. In combination with a part having a door opening and formed at the sides of the door opening with lateral openings, pins disposed in such lateral openings, a sliding door having lateral openings to register with the lateral openings of the part in which the door opening is formed and having recesses upon its inner side in communication with the ends of the lateral openings, pins located in the lateral openings of the door, and a shaft slidably and pivotally mounted upon the door, curved locking arms projecting from the shaft and adapted to operate through the lateral openings of the door and the part in which the door opening is formed and engage the pins arranged in both lateral openings, and stop projections at the ends of the locking arms to enter the recesses in communication with the lateral openings of the door.

In testimony whereof I affix my signature in presence of two witnesses.

RONDO J. BLACKBURN.
